COMBINED DOORKNOB AND ROSE

Charles A. Ellis, Hamden, Conn., assignor to Sargent & Company, New Haven, Conn., a corporation of Connecticut

Application April 25, 1956, Serial No. 41,201

Term of patent 7 years

(Cl. D50—3)

Fig. 1.

Fig. 2.

Fig. 3.

Fig. 4.

Fig. 1 is a side elevational view of a combined door knob and rose embodying my new design;

Fig. 2 is a top plan view thereof;

Fig. 3 is a longitudinal sectional view on line 3—3 of Fig. 1; and

Fig. 4 is a transverse sectional view on line 4—4 of Fig. 1.

I claim:

The ornamental design for a combined door knob and rose, substantially as shown.
